UNITED STATES PATENT OFFICE.

FRANK SCHILLING, OF MUNCIE, INDIANA, ASSIGNOR TO WITTEMANN BROTHERS CO., OF CHICAGO, ILLINOIS.

DESIGN FOR A BOTTLE.

SPECIFICATION forming part of Design No. 32,470, dated April 10, 1900.

Application filed March 12, 1900. Serial No. 8,407. Term of patent 7 years.

To all whom it may concern:

Be it known that I, FRANK SCHILLING, a citizen of the United States, residing at Muncie, in the county of Delaware and State of Indiana, have invented and produced a new and original Design for Bottles, of which the following is a specification, reference being had to the accompanying drawing, forming a part thereof, and in which the figure is a side elevation of a bottle, showing my new design.

As shown in the drawing, the leading or materials features of my design consists of a bottle having the plain side portion A and the ornamented neck and shoulder and base portions. The neck is provided with two parallel annular ribs B B', respectively, and located between these ribs is a series of beads C, extending entirely around the neck. Extending from the rib B' down over the shoulder of the bottle is a series of corrugations D. Below these corrugations is a series of beads E, the corrugations and beads ex-

tending around the bottle. Below these beads is an annular rib F.

Around the lower side or base portion of the bottle is located an annular rib H, and below this rib is a series of beads I. Below these beads are a series of elliptical projections J, and below these projections is another series of beads K. The projections and both series of beads extend around the bottle. Below the series of beads K and forming the lower edge of the bottle is an annular rib L.

Having thus described my invention, what I claim as new, and desire to secure by Letters Patent, is—

The design for a bottle, substantially as shown and described.

In testimony whereof I have hereunto affixed my signature in the presence of two witnesses.

FRANK SCHILLING.
